REFINING OF PETROLEUM DISTILLATES

Carleton Ellis, Montclair, N. J., assignor to Standard Oil Development Company, a corporation of Delaware

No Drawing. Application August 26, 1938,
Serial No. 226,905

5 Claims. (Cl. 196—44)

This invention relates to the refining of petroleum distillates and in particular to those distillates resulting from the pyrolysis or cracking of high-boiling petroleum fractions. It is especially applicable to refining gasolines which have been made by cracking operations and which have been subjected to treatment with sulphuric acid.

Cracked distillates, made by pyrolysis of crude petroleum or any of its various fractions, contain a relatively large proportion of olefinic bodies. The latter may constitute as much as 20, 30 or 40 per cent by volume, or even higher, of the liquid product. The exact proportion will vary considerably depending to a large extent upon the temperature and pressure employed during the cracking operation and also whether or not a catalyst (or catalysts) is used. Generally speaking, the higher the temperature, the lower the pressure, and the presence of one or more catalysts are the factors which favor the formation of larger quantities of olefins or unsaturated hydrocarbons in the resulting distillate or, in other words, a greater degree of unsaturation.

Some of the olefinic hydrocarbons may be unsaturated to such a degree as to give rise to gummy or resinous compounds when the distillate is stored for appreciable periods of time. Such a condition is undesirable, particularly when the liquid hydrocarbons are to be employed as gasoline or fuel for internal combustion engines. In addition, certain types of cracked distillates possess a relatively high content of sulphur-containing compounds. In some instances the latter may act as accelerators of gum- or resin-formation, may effect undue corrosion, for example, of the metal containers or the engine parts with which they come in contact, or may adversely affect the action of lead tetraethyl or other antiknock agents when such agents are blended with the gasoline or other fractions. Also, lower-boiling fractions resulting from the pyrolysis of crude petroleum or its various fractions usually contain color-forming bodies to a greater or lesser extent. The removal, at least in part, of gum- or resin-forming olefins, of sulphur-containing compounds, and of color-forming bodies constitutes the main objects of refining operations.

One method of refining distillates, particularly those boiling within the gasoline and kerosene ranges, comprises treatment with sulphuric acid. In most instances, acid of about 93 per cent concentration or thereabouts is employed, though the use of more concentrated or less concentrated

acid is feasible in some cases. It is generally better when more concentrated sulphuric acid, say 98 per cent, is the refining agent that simultaneously some type of cooling means be used. For example, the distillate and sulphuric acid may be mixed in an agitator equipped with a coil through which is circulated a cold solution of brine or calcium chloride. Afterwards, the mixture is transferred to a settling tank where stratification into two layers occurs. The lower, or acid, layer is withdrawn and the upper, or hydrocarbon, layer then washed (in the same or another tank) successively with water, dilute aqueous alkali and again with water. By distillation of the treated distillate the desired fraction, or fractions, of refined hydrocarbons is secured.

The application of sulphuric acid as a refining agent (as described above) results, among other effects, in the elimination of a substantial proportion of deleterious sulphur-containing compounds, gum- or resin-forming olefins or unsaturated hydrocarbons, and color-developing bodies. However, at the same time there is formed a certain proportion of alkylsulphuric acids and dialkyl sulphates due to interaction of the acid with olefinic hydrocarbons in the oil undergoing treatment. Both types of these sulphuric acid derivatives are soluble, to a very substantial extent, in the distillate undergoing the refining operation. The alkylsulphuric acids may be removed to a considerable degree by the alkali and water washes given the acid-treated distillate. Simultaneously, some of the dialkyl sulphates may be eliminated as these may be hydrolyzed, at least in part, by the alkali and water washes to alkylsulphuric acids and alcohols, and both of the latter (particularly the alkylsulphuric acids) dissolved to some extent in the aqueous layers. Nevertheless a substantial proportion of dialkyl sulphates (and possibly some alkylsulphuric acids) remain dissolved in the hydrocarbon material.

This is particularly disadvantageous since on distilling the hydrocarbons there is considerable decomposition of such sulphur-containing compounds accompanied by the development of acidic bodies, e. g., sulphur dioxide. The presence of the latter is highly undesirable. Being acidic in character it may effect much corrosion, for example, of the metal parts of the still during the distillation operation. This is especially true if some steam is employed (as is done in many instances) as an aid to distillation, since sulphur dioxide reacts with water to furnish sulphurous acid, a highly corrosive substance. Furthermore, if sulphur dioxide remains dissolved for any ap-

preciable period of time in the fraction secured on distillation (especially if olefins are present therein) the liquid becomes badly discolored and considerable formation of soluble and insoluble 5 gums or resins takes place.

Decomposition of dialkyl sulphates to sulphur dioxide, however, need not stop at this point since some of the latter substance, in turn, may react at distillation temperatures with the hydrocarbons present to furnish hydrogen sulphide. This sulphur compound not only is acidic and corrosive in character but also extremely toxic.

I propose to decrease or suppress to a very substantial extent this development and evolution of sulphur dioxide and/or other acid bodies by interaction of dialkyl sulphates (dissolved in the acid-treated distillates) with heavy metal salts of phenolic bodies. Examples of the latter which are suitable for my purpose are phenol (carbolic acid) and cresols. Preferably those metals are employed which form hydrocarbon-soluble derivatives with the phenolic bodies. An illustration of a compound suitable for my purpose is lead phenolate made by reaction of lead oxide with phenol.

Solutions of the metallic salts of phenolic bodies may be prepared in any convenient manner. For example, phenol (carbolic acid) may be admixed with a portion of gasoline and as the mixture is kept stirred there is added, in small portions, a quantity of lead oxide which is slightly in excess of that required to react with the phenol. After reaction is complete the excess oxide can be separated from the solution of metallic phenolate by filtration or decantation. In other instances interaction may be effected by heating a mixture of metallic oxide and phenolic compound, e. g., mercuric oxide and cresol. Afterwards the reaction product is extracted with a hydrocarbon solvent, say benzol, to secure a solution of the phenol derivative.

One procedure whereby I may carry out my invention is as follows: A sample of cracked distillate, which had been treated with sulphuric acid and then washed with aqueous alkali and with water, was added to aqueous alcohol and the solution at room temperature immediately titrated with a standard solution of alkali. This furnished an indication of the combined proportions of alkyl-sulphuric acids and readily hydrolyzable dialkyl sulphates in the distillate. The alcoholic solution is then heated under reflux to effect hydrolysis of the dialkyl sulphates to sulphuric acid, after which the mixture is cooled and again titrated with alkali. This last titration is, therefore, a measure of the quantity of dialkyl esters of sulphuric acid. From these two titrations may be calculated the quantity of metallic phenolate necessary to react with the sulphuric acid derivatives dissolved in the distillate.

The acid-treated distillate is then blended with the requisite volume of hydrocarbon solution of metallic phenolate. After some time a precipitate, presumably the metallic sulphate, slowly settles out and may then be removed by filtration, decantation of the supernatant liquid, or any other convenient means. If desired, interaction may be hastened by gently warming the reaction mixture though this is not necessary to secure good results. Distillation of the filtered or clear distillate can be effected to obtain any desired fraction as a product.

The metallic phenolate may be dissolved in any hydrocarbon solvent in which it exhibits a sub-

stantial degree of solubility. Preferably, however, the solvent should boil within the temperature range corresponding to that of the desired petroleum fraction. For example, if the acid-treated distillate is distilled to yield gasoline, the metallic phenolate may be dissolved in a portion of refined gasoline or in benzol or toluol or in mixtures of these. If the liquid medium is of the type and character of the petroleum distillate being refined, then the medium of course is not the source of any new or unusual compound or compounds which might be introduced into the refined and distilled product. However, I do not limit myself to the solvents just mentioned as many other liquids in which the metallic phenolates are soluble and which are miscible also with the hydrocarbon distillate at hand may be employed.

The following examples will serve as specific illustrations.

Example 1.—Aqueous isopropyl alcohol (100 cc.) was added to acid-treated cracked distillate (50 cc.) and the mixture immediately titrated with standard (0.09446N) alkali. This required 0.89 cc. of alkali solution. The alcoholic mixture was heated under reflux for 1 hour (to effect hydrolysis of dialkyl sulphates) and after cooling to room temperature was again titrated. This time 2.74 cc. of alkali were necessary.

A solution of lead phenolate in gasoline was prepared by adding phenol to a portion of the liquid and slowly incorporating an excess of lead oxide (over that required to react with the phenol) in small portions. After the mixture had stood for several hours, with occasional shaking, all undissolved material was removed by filtration. On analysis it was found that the lead phenolate content of the solution was equivalent to 0.077 gram of lead per 10 cc.

From the above alkali titrations it was estimated that 40 volumes of the lead phenolate solution were required for 450 volumes of the acid-treated distillate. When the two liquids were mixed in this proportion and allowed to stand for several hours, a white precipitate, presumably lead sulphate, slowly settled out. This was removed by filtration and the clear liquid distilled, taking over that portion boiling up to 400° F. During distillation all evolved gases were passed through an aqueous solution of alkali. After distillation was complete, the liquid product was washed with the same solution. The concentration of alkali in the solution was determined before and after it was employed as described. In this manner it was noted that the total acidity developed (gaseous plus that dissolved in the liquid product and calculated as sulphuric acid) was equal to 0.018 per cent.

Another sample of the same acid-treated distillate, without prior addition of lead phenolate, was distilled in like manner. The total acidity which developed in this instance amounted to 0.038 per cent.

Example 2.—Mixed cresols (substantially a mixture of meta- and para-cresol) and lead oxide were added to sweetened (mercaptan-free) straight-run gasoline and the mixture agitated for about 2 hours. At the end of this period any undissolved material was separated by filtration. Analysis of the resulting clear solution indicated it contained 0.0371 gram of lead per 10 cc.

As described in Example 1, a sample of sulphuric acid-treated cracked distillate was titrated with alkali before and after being subjected to hydrolysis in aqueous alcohol. From these titra-

tions it was estimated that 38.5 volumes of the lead cresylate solution were required to react with the alkyl sulphates in 350 volumes of the acid-treated distillate. When distillate and cresylate solution were mixed in this proportion by volume and allowed to stand overnight, considerable white insoluble material was formed. This was removed by filtration and the filtrate then distilled, taking over that portion boiling up to 10 400° F. The proportion of acidic bodies formed during distillation was determined as in Example 1. This was found to be 0.027 per cent.

Another sample of the same acid-treated distillate, without prior addition of cresylate solution, yielded 0.039 per cent acidic bodies when distilled in like manner.

Example 3.—Equal parts by weight of mixed cresols (meta and para) and mercuric oxide were heated for 1 hour at 50° C. The reaction mass was then cooled and leached with benzol. Analysis of the resulting clear solution indicated it contained 0.0336 gram of mercury per 10 cc.

Titration with alkali of a sample of sulphuric acid-treated cracked distillate before and after hydrolysis, as described in Example 1, indicated that 5.5 volumes of the mercury cresylate solution were required to react with the alkyl sulphates in 350 volumes of the treated distillate. When the liquids were mixed in this proportion 30 by volume and allowed to stand for several hours much white precipitate (presumably mercuric sulphate) was formed. This was separated by filtration. The resulting clear filtrate was washed with 5 per cent aqueous caustic soda to eliminate any dissolved cresols. On distillation of the soda washed liquid, taking over the portion boiling up to 400° F., the proportion of acidic bodies formed (and calculated as sulphuric acid) was ascertained to be 0.017 per cent.

40 Another sample of the same treated distillate, without prior addition of mercuric cresylate solution, yielded 0.027 per cent of acidic bodies when distilled in like manner.

Example 4.—The proportion of alkyl derivatives of sulphuric acid in a sample of acid-treated cracked distillate was estimated as described in Example 1. In this instance it was found that 11 volumes of a lead phenolate solution (in gasoline) were required for 450 volumes of the acid-treated distillate. (The phenolate solution contained 0.1425 gram of lead per 10 cc.) A blend of the liquid ingredients in this proportion was made, allowed to stand for several hours at room temperature, separated from the precipitated lead sulphate and then distilled taking over the portion boiling up to 400° F. The total acidity developed during distillation was determined, as indicated in Example 1, and this amounted to 0.002 per cent.

60 Another portion of this same acid-treated distillate was distilled without prior application of lead phenolate. In this case the total developed acidity amounted to 0.024 per cent.

The quantity of alkyl derivatives of sulphuric acid will depend very largely upon the concentration of acid employed in refining and the period of time the acid and cracked distillate are in contact. For this reason the proportion of metallic phenolate required to suppress development 70 or formation of acidic bodies during distillation of different acid-treated distillates will vary considerably. By the term acid-treated distillate as used herein I mean cracked or pyrolyzed petroleum (or its various fractions) which has been subjected to the action of sulphuric acid.

I am aware that many substances of an alkaline nature, such as soda ash, caustic soda, or alkali soaps of fatty acids have been proposed as agents for the suppression of sulphur dioxide and other acidic bodies during the distillation of acid-treated cracked distillates. Such compounds, however, exhibit a limited solubility in petroleum hydrocarbons. Furthermore, it appears they are active agents mainly at elevated temperatures. For example, these alkaline substances (either as such or as concentrated aqueous solutions) may be incorporated with the acid-treated hydrocarbons as the latter are being distilled. Or the hydrocarbon liquid may be pre-treated with the alkaline agents (generally at 10 elevated temperatures and under high pressures) 15 before distillation.

The refining agents I prefer, according to my invention, are compounds which are soluble in petroleum hydrocarbons and which interact with 20 alkyl derivatives of sulphuric acid in such a manner as to effect elimination of those bodies which decompose with the formation of acidic materials during distillation. Furthermore, those compounds suitable for my purpose are heavy metal 25 salts derived from phenolic bodies, exhibit substantial solubilities in hydrocarbons and interact at room, or working, temperatures with the esters of sulphuric acid present in such liquid 30 hydrocarbons.

It should be noted that interaction of olefins and sulphuric acid generally furnishes secondary or tertiary dialkyl sulphates or alkylsulphuric acids. When such dialkyl sulphates react, for example, with lead phenolate the products are 35 lead sulphate and alkyl phenyl ethers. The latter compounds therefore will contain an aromatic nucleus and a branched-chain alkyl radical. Both of these factors should cause the ethers (provided they possess the requisite boiling range) 40 to exhibit high antiknock values when employed in fuels, such as gasolines, intended for internal combustion engines of the spark-ignition type. Gasolines obtained from acid-treated cracked distillates, subjected to the action of phenolic derivatives (according to my invention) and subsequently distilled, may contain a small proportion 45 of such alkyl phenyl ethers which should enhance their value as motor fuels.

On the other hand, alkyl sulphuric acids may 50 interact with metallic phenolates to give the corresponding phenolic bodies and the metallic salts of alkylsulphuric acids. Distillation of acid-treated distillates, which contained alkylsulphuric acids and were treated with metallic 55 phenolates, may yield fractions having a small proportion of free phenolic bodies. Since the latter are known to be good antioxidants their presence, in small amounts, should render the distilled fraction less susceptible to deterioration attributable to oxidation. In the case of cracked gasolines, for example, the liquid would be less likely to develop gum during storage or when in contact with the atmosphere.

60 By the term heavy metal as used herein I mean 65 those metallic elements which are not classed either as alkalies (e. g., sodium, potassium, lithium) or as alkaline earths (for example, calcium, strontium or barium). Heavy metals are generally characterized by their ability to form 70 sulphides which are substantially insoluble in water and not readily decomposed thereby.

75 What I claim is:

1. The process which comprises treating a sulphuric acid-treated cracked petroleum distillate 75

with a hydrocarbon-soluble heavy metal salt of a phenolic body selected from the class of substances consisting of phenol and its homologues, allowing insoluble metallic compounds to form and separating said insoluble compounds, whereby the ability of said distillate to develop acidic compounds on distillation is suppressed.

5 2. The process which comprises treating a sulphuric acid-treated cracked petroleum distillate with a hydrocarbon-soluble lead salt of carbolic acid, allowing insoluble lead compounds to form and separating said insoluble compounds, whereby the ability of said distillate to develop acidic compounds on distillation is suppressed.

3. The process for suppressing development of acidic compounds during the distillation of sulphuric-acid treated cracked petroleum distillates which comprises treating said distillate with a hydrocarbon-soluble heavy metal salt of a phenolic body selected from the class of substances consisting of phenol and its homologues.

4. The process, according to claim 3, in which the phenolic body is carbolic acid.

5. The process, according to claim 3, in which the hydrocarbon-soluble salt is a lead salt.

CARLETON ELLIS.
